(57) **CLAIM**

I claim the ornamental design for a flanged gauge ring, as shown and described.

DESCRIPTION

FIG. 1 is a top perspective view of a flanged gauge ring, showing my new design;

FIG. 2 is a left side perspective view thereof;

FIG. 3 is a right side perspective view thereof;

FIG. 4 is a top view thereof; and,

FIG. 5 is a bottom view thereof.
